UNITED STATES PATENT OFFICE

98,262

DESIGN FOR A COASTER

Michael Leff, Buffalo, N. Y.

Application November 5, 1935, Serial No. 59,393

Term of patent 7 years

To all whom it may concern:

Be it known that I, Michael Leff, a citizen of the United States, residing at Buffalo, in the county of Erie and State of New York, have invented a new, original, and ornamental Design for Coasters, of which the following is a specification, reference being had to the accompanying drawing, forming a part thereof.

Figure 1 is a front view of the coaster embodying my design. Figure 2 is a rear view thereof. Figure 3 is an edge view of the same.

The coaster of my design consists of a sub-

stantially disk-like body having one or more portions or projections extending from the periphery thereof to form a base to receive matter appropriate or corresponding to a given advertisement of a product and having a bridge-bidding indicator thereon, and wherein the whole serves as a combined coaster, bridge-bidding indicator and advertising novelty.

I claim:

The ornamental design for a coaster, substantially as shown and described.

MICHAEL LEFF.
